UNITED STATES PATENT OFFICE.

JOHN C. SUTTON, OF ROCKFORD, ILLINOIS, ASSIGNOR TO SUTTON SHOPS, INC., OF ROCKFORD, ILLINOIS, A CORPORATION OF ILLINOIS.

DESIGN FOR A CAP.

Application filed July 18, 1927. Serial No. 22,793. Term of patent 7 years.

To all whom it may concern:

Be it known that I, JOHN C. SUTTON, a citizen of the United States, residing at Rockford, in the county of Winnebago and State of Illinois, have invented a new, original, and ornamental Design for a Cap, of which the following is a specification, reference being had to the accompanying drawing, forming part thereof.

The invention comprises a skeleton cap presenting contrasting appearances between the inserts and the border edging substantially as shown.

In the drawing, wherein I have represented by surface shading the sheen of the inserts—

Fig. 2 is a front view thereof.

I claim:

The ornamental design for a cap, substantially as shown and described.

JOHN C. SUTTON.
